(57) **CLAIM**

The ornamental design for a flushometer cover, as shown and described.

DESCRIPTION

FIG. 1 is a front elevational view of a flushometer cover showing my new design;

FIG. 2 is a top plan view thereof;

FIG. 3 is a rear view thereof;

FIG. 4 is a bottom view thereof;

FIG. 5 is a right side view thereof; and,

FIG. 6 is a left side view thereof.

The broken lines shown in FIG. 1 illustrate environmental subject matter only that form no part of the claim. The broken lines shown in FIG. 4 depict portions of the flushometer cover that form no part of the claim.
